J. L. GOBEILLE.

HEATING STOVE.

No. 18,333.

Patented May 22, 1888.

UNITED STATES PATENT OFFICE.

JOSEPH LEON GOBEILLE, OF CLEVELAND, OHIO, ASSIGNOR TO THE CHANNON-
EMERY STOVE COMPANY, OF QUINCY, ILLINOIS.

DESIGN FOR A HEATING-STOVE.

SPECIFICATION forming part of Design No. 18,333, dated May 22, 1888.

Application filed January 19, 1888. Serial No. 261,336. Term of patent 7 years.

To all whom it may concern:

Be it known that I, JOSEPH LEON GOBEILLE, residing at Cleveland, county of Cuyahoga, State of Ohio, have invented and produced a new and original Design for Heating-Stoves, of which the following is a specification, reference being had to the accompanying engraving of a heating-stove having said design, and forming a part thereof.

10 This design embraces several new and distinctive parts and combinations of parts which go to make up the whole design, as hereinafter specified.

15 One integral part of this design is the shape and ornamentation of the front door, A, which ornamentation consists of a large upright spray of foliage, a, on the oblong space on the face of said door, extending from the damper-slide nearly to the top thereof, and spread

20 across the said space. Below the said spray a, upon the small faces between the damper-slide interstices in said door, are four upright rows, b, of six-pointed stars, and above said spray a is a horizontal row of conventional

25 blooms, c, between two parallel raised right lines. Rising above the center of said spray is a compound linear figure, d, of triangular effect, all of said ornamentation except the rows of six-pointed stars b aforesaid displayed

30 upon a plane roughed surface. Extending around said front door, A, is a geometric linear decoration, e, and concentric with the said last-named decoration e to the edge of but not across the bottom of said front door, A, extends a row of arrow-heads, f, their butts against the edge of said door A and their points toward said decoration e, all as shown.

35 A further distinctive part of this design is the shape and ornamentation of the front B, 40 which ornamentation consists of a row, g, of decorative blooms, twigs, and leaves extending around the door-opening, except below the line of the bottom thereof, and concentric with said row g, but extending entirely around said front B, a row of spear or arrow heads, h, ra-

diating from the center of said front outward. Above the last-described decoration, upon the cresting or finish of said front B, displayed on a rough plane ground on the right and left ends thereof, respectively, are similar ornamental branches, i and i', disposed correspondently to each other, all as shown.

45 A further distinctive part of this design is the shape and ornamentation of the back C, which ornamentation consists upon the front side thereof, upon the cresting or finish of said back C, of a concentric kaleidoscopic design, m, in the center thereof, and on either hand of said kaleidoscopic design m, upon rough ground, similar branches, i' i', of foliage and 55 blooms, similar also to those upon the front of the finish or cresting of the front B, and disposed correspondently to each other, all as shown.

50 I claim as new in a design for a heating-stove—

1. The design for a front door herein shown and described, the same consisting of the branch a, the rows of stars b, the horizontal row of blooms c, the linear figure d, the geometric decoration e, and the row of arrow-heads f.

2. The design for a front herein shown and described, the same consisting of the decorative foliage g, the row of arrow-heads h, and the ornamental branches i and i'.

3. The design for the back having the top ornamentation on the front thereof, herein shown and described, the same consisting of the kaleidoscopic figure m and the branches 70 i' and i'.

4. The whole design unitarily embracing the design for a front door, a front and front of a back, all substantially as herein shown and described.

JOSEPH LEON GOBEILLE.
